**FRAMEWORK STRUCTURES FOR SUSPENDED
CEILING AND LIGHTING SYSTEMS**

Robert A. D. Schwartz, 81 Kemberlin Heights Drive, Oakland, Calif., and Stephen W. Lindheim, 1146 Keeler St., Berkeley, Calif.

Application May 25, 1960, Ser. No. 31,619, now Patent No. 3,146,956, which is a division of application Ser. No. 625,065, Nov. 29, 1956, now Patent No. 2,956,150. Divided and this application Aug. 26, 1964, Ser. No. 392,215

6 Claims. (Cl. 240—9)

This invention relates to improvements in framework structures for suspended ceiling and lighting systems, the present application for Letters Patent thereon being a division of our application Ser. No. 31,619, filed May 25, 1960, now Patent No. 3,146,956, which in turn is a division of our application Ser. No. 625,065, filed Nov. 29, 1956, now Patent No. 2,956,150, dated Oct. 11, 1960, which latter application is a continuation-in-part of our application Ser. No. 457,844, filed Sept. 23, 1954, now Patent No. 2,888,113, dated May 26, 1959.

As explained in some detail in our aforesaid application Ser. No. 31,619, it has become common practice in modern lighting and ceiling construction to combine ceiling and lighting means into an integrated ceiling system built upon a framework structure suspended from a permanent ceiling or roof and which supports both the usually modular ceiling panels and a plurality of tubular (fluorescent) lamps conventionally disposed at a level above said panels but which, in the case of light-reflecting ceiling panels, may also be disposed at a lower level than said panels.

A problem arising in such an integrated ceiling construction is that of making suitable accommodation for the wiring necessary for the tubular lamps, which of course must be masked from view and at the same time be so located as to be reasonably accessible. Labor and material-cost factors involved in installing the lamp wiring also dictate that the wiring system be simple and of a nature as to eliminate duplication of parts and also of a type as permits speedy, low-cost installation.

It is therefore an object of the present invention to provide an improved, simplified framework structure for suspended ceiling and lighting systems, which, in addition to incorporating means for supporting the ceiling panels and the plurality of tubular lamps that are usually employed in such a system, also defines hidden yet readily accessible and conveniently located raceways for the wiring for the tubular lamps.

A more particular object of the invention is the provision of a framework structure for a suspended ceiling and lighting system as aforesaid which is made up of longitudinal members or runners and cross members connected thereto preferably in grid fashion, wherein either or both said longitudinal members and cross members are so constructed and configured as to provide not only the horizontal flanges required to support the ceiling panels along edges thereof, but also to provide one or more channel-like raceways for the wiring extending to the tubular lamps also supported on said framework.

Another object of the invention is the provision of a framework member for use in suspended-ceiling framework construction comprising an upper elongate portion of channel section defining an open-top raceway for wiring running to electrical lighting means associated with the suspended ceiling and a lower elongated portion of inverted T-bar section depending from said upper portion and including coplanar flanges extending horizontally outwardly from the vertical leg of said T-bar section, wherein the width of the upper raceway-defining portion

of the member does not exceed the total width of said flanges, whereby framework members characterized as aforesaid may be combined with simple, inverted T-bar framework members having the same flange width, without the members of the invention giving different appearance than those of simple T-bar section, when all are viewed from below, and further whereby framework members having the special configuration and channel width as aforesaid may be employed in the framework of luminous ceilings of the type which mount lighting means above the framework, without casting a shadow discernible from below the ceiling level.

The above and other objects will become apparent from the following detailed description of the framework structure of the invention, wherein reference is had to the accompanying illustrative drawings, in which

FIG. 1 is a fragmentary view in perspective, partly in section, of an integrated ceiling and lighting system incorporating the improved framework structure of the invention;

FIG. 2 is an enlarged fragmentary view, in perspective, showing in greater detail than does FIG. 1 the configuration, in transverse section, of one of the longitudinal runners or members of the framework structure shown in FIG. 1, as well as its capability of providing a raceway for electrical wiring;

FIG. 3 is a view similar to FIG. 1, but illustrating a somewhat modified form of framework structure than illustrated in FIG. 1; and

FIG. 4 is a view illustrating yet another form of framework structure for a suspended ceiling and lighting system according to the present invention, wherein both the longitudinal members or runners and the cross members of the framework grid are configured to provide channel-like raceways for the accommodation of both the longitudinal and cross wiring for the lamps employed in the system.

Referring to the drawings in greater detail, and first to the form of ceiling framework structure illustrated in FIGS. 1 and 2 and therein generally designated F, such framework structure is shown to be comprised by a plurality of parallel, laterally spaced, longitudinal members or runners 10 and a plurality of cross members 12 extending between and interconnecting said longitudinal runners in manner as to form a grid structure, of which one such longitudinal member and one such cross member are partially shown. Said framework structure is adapted to be supported from the permanent ceiling of a room or from rafters of a building, as by means of a plurality of hanger straps 14 of inverted U-shape (only one being shown), whose side legs are adapted to be affixed at their free ends to outwardly projecting upper-edge flanges 10x, 10y provided on the longitudinal members 10 of said framework structure and which mount eye-bolts 16, to the eyes of which are attached the lower ends of suspension wires or cables 18 whose upper ends (not shown) extend to and are secured to the aforesaid permanent ceiling or said building rafters, for example.

At spaced intervals along their respective lengths, the aforesaid longitudinal runners 10 of adjacent pairs thereof are mounted opposed pairs of upright pedestals 20, which in turn mount sockets 22 in which the ends of transverse tubular lamps 24 are supported. Each said pedestal is preferably fashioned from identical upright half sections 24a, 24b which are secured in back-to-back relation, and are moreover formed with mating hollow ribs 26 which together define a vertical duct for electrical wiring extending to the lamp sockets 22.

Said longitudinal runners 10 are further provided along their bottom edges with oppositely directed, horizontal

coplanar flanges 10a and 10b, and similarly the cross members 12, which in the FIGS. 1 and 2 form of framework structure comprise simple inverted T-bars, are provided with oppositely disposed, coplanar horizontal flanges 12a, 12b. Thus, each of the openings in the grid-form framework provided by said longitudinal and cross members are bounded by coplanar, upwardly facing flanges 10a, 10b and 12a, 12b which provide supporting ledges for a luminous ceiling panel 28, it being understood that said panels are repeated throughout the full area of the framework grid, thus in practical effect providing a modular luminous ceiling system.

From the construction so far generally described, it will be understood that the framework structure F defined by the longitudinal members or runners 10 and the cross members 12 is one intended to be suspended from a permanent ceiling or other fixed building part above same, and that it serves to support a plurality of usually luminous ceiling panels along all four edges thereof and also a plurality of tubular lamps which are disposed above the luminous ceiling panels and which preferably extend crosswise between adjacent pairs of longitudinal runners of the plurality of such runners in part making up the framework structure. It will also be seen that such a framework structure F provides for spacing of the lamps 24 independently of the grid opening or modules formed by its members 10 and 12, and also for varying the spacing of the lamps above the panels 28 simply by varying the height of the pedestals 20. And of course said framework structure can be suspended at any appropriate height below the permanent ceiling.

According to one form of longitudinal member or runner 10 employed in said framework structure which is best shown in FIG. 2, wherein runner configuration in transverse section is depicted, said runner comprises an open-top channel portion 30 defined by laterally spaced, vertical side walls 30a, 30b extending from a horizontal bottom wall 30c, and a lower portion 32 having inverted T-bar section and including a vertical web or plate 32a depending substantially centrally from said channel bottom wall 30c and which carries along its lower edge the aforesaid oppositely directed, coplanar flanges 10a, 10b for supporting the luminous ceiling panels 28. It is a feature of the invention that the width of said channel portion 30 does not exceed the total of the width of the two coplanar flanges 10a, 10b of the lower portion of T-bar section. Hence, it will be appreciated that while said channel portion defines an elongated raceway for the longitudinal wiring necessary for the tubular lamps 24 supported by said longitudinal members or runners, such cannot be seen from below nor will it cast a shadow discernible from below.

For such cross wiring as may be required for the lamps 24 extending between adjacent pairs of the longitudinal members or runners 10, cross wiring means generally designated 34, 36 (FIG. 1) are provided, it being observed that such will communicate with the longitudinal wiring raceways provided by the channels 30 of said runners 10 as may be necessary.

A raceway cover 38 (FIG. 1) is provided, such being preferably fashioned of sheet metal having sufficient resilience as to permit its side edges to be snapped into facing grooves 36a, 36b formed in the side walls of the channels 30 along their upper edges. Preferably, to provide for ready access to the wiring raceway, and also for communication between said raceway and said pedestals 20 and said cross wiring means 34, 36, the raceway covers 38 are fashioned in sections having substantially shorter length than that of the longitudinal runners 10, and which may be spaced from one another at appropriate intervals along the length of the channel. Further details concerning the cover-section spacing and related features will be found in our aforesaid Patent No. 2,888,113.

FIG. 2 illustrates that the framework cross members 12 of inverted T-bar section as stated above are secured at each end thereof to a longitudinal member or runner 10 by a connector member having a head portion 40 which is received in the facing, vertical aligned guideways 42 provided on each face of the vertical web or flange 32a of the lower inverted T-portion 32 of said longitudinal member, and further having a projecting tongue 44 which, after being passed through a slot in the end of the vertical web of the respective T-bar 12, is then bent back on said web. Further details regarding the construction, mounting and manner of operation of said connector members will be found in our patent No. 2,888,113.

FIG. 2 illustrates a further feature of advantage of suspended-ceiling framework members 10 especially configured and dimensioned as aforesaid, namely, that such may be combined with simple T-bar members corresponding to that designated 12, without said members 10 being distinguishable from said simple T-bar members 12 when all are viewed from below. This assumes, of course, that both forms of framework members 10 and 12 will have the same flange width, but this assumption is in accordance with standard practice in the design of ceiling framework of the type which supports modular ceiling panels along the outer edges thereof, of making all panel-supporting flanges of the same width.

According to the modified form of framework structure shown in FIG. 3, the cross members of the framework (or the particular cross member or members which will carry the cross wiring), rather than the longitudinal members or runners thereof, have the combined T-bar and channel configuration previously described for said longitudinal runners, whereby the cross members may enclose cross wiring within their length which extends transversely between the longitudinal runners to which they are end-connected. In this form of framework structure, the longitudinal members or runners designated 48 are shown to have a simple channel section, whose channels 50 are defined by horizontally spaced, upright side walls 50a, 50b and a bottom wall 50c. Said longitudinal channel-sectioned members or runners are adapted to provide longitudinal raceways for the wiring for the tubular lamps 24 extending between adjacent members as aforesaid, and they are also provided with oppositely projecting, horizontal, coplanar flanges 52a, 52b disposed to project outwardly from the lower edges of said channel sides and functioning as the aforesaid flanges 10a, 10b in forming opposed supporting ledges for adjacent luminous ceiling panels 28. For further details regarding such longitudinal members or runners 50 characterized by the aforesaid substantially straight channel configuration, reference may be had to our aforesaid Patents Nos. 2,888,113 and 2,956,150.

The modified cross member designated 60 in FIG. 3 form of framework structure comprises an upper channel portion 62 defined by spaced vertical side walls 62a, 62b and a connecting bottom wall 62c, and by a lower portion 64 of inverted T-section consisting of an upright plate or web 64a depending substantially centrally from said bottom wall 62c of the upper channel portion and carrying horizontal panel-supporting flanges 66a, 66b which extend in opposite directions from the lower edge of said plate or web portion and which are coplanar with one another and also with the flanges 52a, 52b of the associated longitudinal member 50. Said combined channel and T-bar type cross member 60 is adapted to be secured to the longitudinal members or runners with which it is associated as by connector members 40, 44 similar to those which effect the securing of the straight T-bar cross member 12 as earlier described, and hence no further description of this securing is here included.

At this point of the description of the FIG. 3 form of cross members 60, it is to be particularly noted that

the upright plate or web 64a of the lower T-bar portion of said cross member has increased height as compared to that of the vertical web of the cross member of simple T-bar section employed in the FIGS. 1 and 2 framework structure, as enables the adjacent ends of the channel portions 62 of tandem-related cross members to extend over and rest on the upper edges of the side walls of the channels of the longitudinal runners or members 48. Such an arrangement makes it exceedingly simple to establish communication between the longitudinal wiring raceways provided by the channels 50 of the longitudinal members or runners and the cross-wiring raceways provided by the upper channel portions of the cross members having the section shown in FIG. 3.

The channels 50 of the longitudinal members 10 are adapted to be closed on top by a longitudinal cover strip 70 corresponding to the cover 38 of the FIGS. 1 and 2 form of framework structure. Similarly, the open top channel portion 62 of each channel and T-bar-sectioned cross member 60 is adapted to be closed on top by a top cover 74 adapted to be snapped into facing grooves provided along the upper edges of the side walls defining said channel portion. Preferably, said cover 74 is of a length as to extend between the ends of tandem-related cross members resting on a longitudinal member and carries an inverted U-shaped bridging member 76 of width as to extend between the side walls 62a, 62b of the channel portions of the so-related cross members. Illustratively, the bridging member is secured to the under face of the cover 74 by rivets 78 and its side legs are sufficiently long that they extend downwardly into engagement with the cover 70 of the longitudinal channel 50. It will of course be understood that said latter cover may be broken apart or pierced in its area covered by the bridging member 76 so as to permit wiring to be run upwardly from a longitudinal raceway to an associated cross raceway.

The advantage of the FIG. 3 form of framework structure over that of the FIGS. 1 and 2 form thereof is that the cross member itself provided with a wiring raceway for such cross wiring as may be necessary for the lamps supported on said structure eliminates the need of the separate cross-wiring means 34, 36 shown in FIG. 2, for example.

FIG. 4 illustrates yet another form of framework structure according to the invention wherein both the longitudinal members or runners and the cross members thereof (or some of them) have the combined channel and T-bar configuration characterizing only the longitudinal members or runners 10 of the FIGS. 1 and 2 form and only the cross members 60 of the FIG. 3 form of framework. More particularly, a longitudinal runner designated 80 is shown to have configuration in transverse section identical with that of the longitudinal member or runner 10 shown in FIG. 2, and a cross member designated 90 associated therewith has configuration in transverse section which is generally that of the cross member shown in FIG. 3, differing from the latter only in respect to the vertical plate or web member 94a of its lower inverted T-bar portion 94 having the increased height as enables its upper channel portion 92 to extend over onto and to rest on the upper edges of the channel portion 30 of the longitudinal member when its bottom panel-supporting flanges are coplanar with those of the inverted T-bar portion of said longitudinal member.

Thus, in the FIG. 4 form of framework structure also, the provision of a channel in one or more of the cross members serving as a raceway for cross-wiring does away with the necessity of providing cross-wiring conduits or ducts entirely separate from the cross member, as characterized the FIG. 1 form of structure and also certain of the framework structures disclosed in our prior issued Patent No. 2,956,150 and our aforesaid application Ser. No. 31,619. Accordingly, both the

FIGS. 3 and 4 framework structures require a reduced number of parts and thereby makes possible simpler and less expensive installation procedure, as compared to that for the framework structure employing the separate cross-wiring ducts or conduits such as those designated 34, 36 in FIG. 1.

As explained in my aforesaid application Ser. No. 31,619, the basically T-bar type frame member which incorporates a channel-form raceway as herein contemplated for the main and/or cross wiring has the further advantage that it is inherently stronger and more rigid than either the conventional channel-section or plain or T-bar form of frame member and thus its use in a ceiling framework results in the framework structure and thereby the entire ceiling having increased strength, load bearing capacity and resistance to shocks and vibrations, as compared to the ceiling framework fabricated from longitudinal runners and cross members having the more conventional section or sections. In addition, wiring raceways which extend the full lengths of both the longitudinal members or runners and of the cross members which interconnect same (or some of them as may be necessary) makes for great flexibility in the wiring system, which is an added feature of advantage in the installation of luminous ceilings generally, and more particularly in irregularly or non-symmetrically shaped buildings or rooms thereof.

As many changes could be made in carrying out the above constructions without departing from the scope of the invention, it is intended that all matter contained in the above description or shown in the accompanying drawings shall be interpreted as illustrative and not in a limiting sense.

We claim:

35. 1. A ceiling framework member for an integrated ceiling and lighting system comprising an upper elongated portion of upright channel section defining an open-top electrical wiring raceway for enclosing wiring running to electrical lighting means in part supported from said member and a lower elongated portion of inverted T-bar section depending therefrom and including a planar vertical leg and a pair of coplanar horizontal flanges integral with and projecting outwardly and in opposite directions from the lower edge of said leg and providing ceiling-panel supporting means, the width of the channel section being substantially equal to the total width of said flanges.
40. 2. A ceiling framework member according to claim 1, wherein said upright channel portion and said lower portion of inverted T-section are integral one with the other.
45. 3. A ceiling framework member according to claim 1, and further including an elongate cover for and closing the open top of the channel, and means extending along and being integral with the top edges of said upper portion for demountably securing the cover in position to close the open top of the channel.
50. 4. A ceiling framework member according to claim 1, wherein said portion of inverted T-bar section is provided with opposed means extending along both the top and bottom edges of its vertical leg and which cooperate with the opposite plane faces of said leg in defining a pair of oppositely facing slideways for connector means adapted to secure the ends of other framework members to said framework member.
55. 5. A framework structure for a suspended ceiling and lighting system including, in combination: a plurality of longitudinal members connected together in manner as to form a supporting framework for ceiling panels and for ceiling lighting means; at least certain of said members each comprising an upper elongate portion of open-top channel section and a lower elongate portion of inverted T-bar section depending therefrom and including a planar vertical leg and a pair of coplanar horizontal flanges projecting outwardly and in opposite directions

from the lower edge of said leg and providing support means for ceiling panels disposed to the opposite sides of said members, suspension means carried by said framework for suspending same from above; means on said framework for supporting tubular lamps thereon; the channels of said upper portions of said certain members forming raceways for the wiring for said lamps and said upper portions and the coplanar flanges on the lower portions of said certain members having substantially the same width.

6. A framework structure for a suspended ceiling and lighting system according to claim 5, wherein each said lower portion of inverted T-bar section is provided with opposed means extending along both the top and bottom edges of its vertical leg and which cooperate with the opposite planar faces of said leg in defining a pair of oppositely faced slideways for connector means adapted to secure transversely extending framework members to said framework member.
